APPARATUS FOR BLACKING THE EDGES OF SOLES FOR SHOES

Albert V. Shortell, Manchester, N. H.

Application September 30, 1937, Serial No. 166,611

6 Claims. (Cl. 91—51)

This invention relates to automatic apparatus for coating the edges of shoe soles with blacking or liquid preparations and the principal purpose of the invention is to provide a simple, efficient and economical machine for blacking the entire peripheral edge of the sole, in a single and continuous preparation, so that the blacking material will be applied uniformly to the edge and will not spread over the upper or lower surfaces of the sole at the margins thereof.

Another object of the invention is to provide an automatic, power driven machine which comprises mechanism for holding the sole in a substantially vertical plane and causing the sole to rotate or turn in said vertical plane, so that its entire peripheral edge is presented to a wiping element or roller which is mounted adjacent said mechanism and is associated with a reservoir for the blacking or other liquid coating material, and which also serves to guide the sole during its rotative movement.

Further objects reside in the various adjustments and other novel features of the apparatus hereinafter described in conjunction with the accompanying drawing illustrating a preferred embodiment of the machine, as pointed out in the appended claims. In said drawing,

Fig. 1 is a plan view of the improved blacking machine with a shoe sole mounted in operative position;

Fig. 2 is a side elevation thereof;

Fig. 3 is an end view of the machine looking to the right of Fig. 1, with the shoe sole omitted; and

Fig. 4 is a fragmentary section taken on line 4—4 of Fig. 1.

The machine comprises a base 11, having upstanding arms 12 and 13 provided with journals 14 and 15, respectively, which carry a drive shaft 16 having a pulley 17 at one end and a knurled disc or collar 18 at its other end; an auxiliary shaft 19 mounted in laterally projecting arms 20 and 21 of the journal members 14 and 15, respectively, substantially parallel to the shaft 16, the shaft 19 having a gear 22 meshing with a gear 23 on shaft 16, and having a ring or collar 24 mounted on its opposite end and in operative relation to the knurled disc 18; a sole guide 25 adjustably mounted to the bracket 20 by an arm 26; and an inking roller 27 adjustably connected to the arm 26 by a bracket 28. A reservoir 29 for the coating liquid is adjustably mounted by brackets 30 and 31 to the base 11; and said reservoir is fed and kept at a substantially uniform level by a bottle 32 which is inverted into a trough 33 communicating with said reservoir, in a manner well understood. The inward wall of the reservoir or container 29 preferably extends upwardly and toward the face of the roller 27, as

indicated at 59, to serve as a splash guard when the machine is operating at high speed.

The driven shaft 16 is stationary in its journals, but the shaft 19 is so mounted that the ring or collar 24 at its outer end may be moved toward or from the knurled disc 18, to accommodate various thicknesses of sole leather therebetween. As shown in Fig. 4, the shaft 19 is pivotally mounted in the bracket 21 by means of a pair of pointed screws 34 which form pivot bearings 10 against a collar 35 surrounding said shaft in the journal of said arm 21. Shaft 19 extends through a slot 36 in the bracket 20, so that it may swing laterally therein, and its swinging movement is restrained by a tension spring 37 located in a hole 15 bored lengthwise in said bracket. The spring bears against said shaft at one end, and against a plate 39 at its outer end; and its tension may be adjusted by varying the position of screws 40 which fasten said plate to the end of the arm 20. 20 A spindle 41 extends through the plate and arm to hold the spring in operative position. Thus, the members 18 and 24 which constitute the gripping and driving or feeding elements of the machine are constantly urged toward each other to grip the sole 42 therebetween, under the resilient action of the spring 37 which will yield to accommodate the thickness of the sole.

The sole guide 25 is mounted behind said driving elements at or slightly above a plane passing through their axes; and its supporting arm 26 is slotted at its rearward end 43, so that the position of said arm and its guiding elbow 25 may be adjusted forwardly or rearwardly, by the screw 44 which fastens the arm to the bracket 20 at the slot 43.

The blacking or inking roller 27 is also adjustably mounted to the arm 26 by the bracket 28 which is pivotally attached at 56 to a connecting bracket 45, the latter being pivotally connected to arm 26 by a screw 46 which extends through a slot 47 therein. Hence, the position of the inking roll may be varied forwardly and rearwardly as well as angularly with respect to the guide 25 and the driving or feeding members 18 and 24.

The lowermost portion of the inking roll is located in the reservoir 29, so that its periphery is coated with the blacking or other liquid 57, in which it is immersed; and the position of the reservoir may be adjusted according to the location of the roll 27 by varying the relative position of its supporting brackets 30 and 31 at the screw and slot connection 48, 49, or at the screw and slot connection 50, 51 on the base 11.

The blacking roll 27, as well as the elbow 25, 55 serves as a guiding abutment for the edge of the sole gripped between the driving or feeding members 18 and 24, the point of contact between the periphery of the roll 27 and the sole edge (at 52, Fig. 2) being located below and forwardly 60

of the guiding elbow 25. Hence, when said driving or feeding members are rotated on their respective shafts to move the sole downwardly in a vertical direction, the edge of the sole is forced 5 against the guide 25 and the periphery of the roll 21, and the sole is thus caused to rotate or turn, in a vertical plane, in such a manner that a single revolution will bring its peripheral edge into uniform contact with the wet surface of the blacking roll 21, which is rotated on its axis by 10 the motion of the sole against said surface. Said roll is preferably made of rubber or other suitable material having a relatively hard and flat periphery to present an edge to edge contact with 15 the periphery of the sole, so that the blacking or other liquid coating material is thoroughly applied to the sole edge but will not wipe or spread over the edge onto the flat surfaces of the sole. It will be understood that the drive 20 shafts and the feeding mechanism may be operated by any suitable source of power applied to the pulley 17, and it will be appreciated that the sole is rotated and blackened or coated on its edge with extreme rapidity, thereby effecting a 25 very substantial saving in the time and labor required in performing this operation by hand, as well as ensuring a neater and more uniform result.

It will also be understood that the rough or 30 flesh side of the leather sole is presented to the knurled disc or feed roll 18, when the sole is placed in the feeding mechanism, and that the smooth surface of the complementary feed roll 24 engages the grain side of the sole so that 35 the appearance of the latter will not be marred; and that any other suitable feed rolls may be used in place of the specific types illustrated and described herein. Other changes or modifications in the structural details of the machine 40 herein disclosed may be utilized without departing from the spirit of this invention as defined in the following claims.

I claim:

1. Edge-coating apparatus of the character described, comprising opposed feed rolls for gripping the margin of a sole and moving said margin lengthwise, guides bearing against the edge of the sole at opposite sides of the point of contact of the feed rolls, to cause the sole to turn peripherally under action of the feed rolls, one 50 of said guides being a roller for coating the sole edge, and a reservoir for coating liquid located to receive said roller.

2. Edge-coating apparatus of the character described, comprising a pair of feed rolls arranged 55 to grip the margin of a leather sole and hold the sole in a substantially vertical plane, a guiding abutment located to engage the edge of the sole gripped by said rolls, an edge-coating and guiding roller mounted to engage the periphery of the sole, a reservoir for the coating liquid disposed in operative relation to said roller, and means for driving the feed rolls to move the sole downwardly, the said abutment and the engaged 60 edge of said roller being disposed on opposite sides of a vertical plane passing through the feed rolls so that the sole is forced into constant engagement with said guiding elements and is turned by the feed rolls until its entire edge is 65 coated by said roller.

3. Edge coating apparatus of the character described, comprising a pair of opposed feed rolls

arranged to grip the margin of a leather sole and hold the sole in a substantially vertical plane, a guiding abutment located above the point of contact between the feed rolls and the sole to engage the edge of the sole gripped by said rolls, 5 an edge-coating and guiding roller mounted below said point of contact to engage the periphery of the sole, a reservoir for the coating liquid disposed in operative relation to said roller, and means for driving the feed rolls to move the sole 10 downwardly, so that the sole is forced into constant engagement with said guiding elements and is turned by the feed rolls until its entire edge is 15 coated by said roller, one of said feed rollers being movable away from the other, and spring means yieldingly resisting said movement, so that soles of varying thickness may be gripped between said rolls.

4. Edge-blackening apparatus of the character described, comprising a pair of opposed feeding members resiliently mounted with respect to each other for movement into gripping relation with the marginal edge of a shoe sole, said members being rotatable on horizontal axes to feed the sole downwardly, a pair of guiding abutments 25 positioned to contact the edge of the sole on opposite sides with respect to the downward force applied to the sole, one of said guiding abutments comprising a coating roller turned by contact with the sole, and means for applying blacking 30 to said roller.

5. Apparatus for blacking the edges of shoe soles, comprising a pair of horizontal shafts, one shaft being pivoted for angular movement with respect to the other, resilient means tending to 35 resist relative movement and to urge the shafts toward each other, opposed feed rolls carried by the respective shafts and adapted to grip the margin of the sole therebetween, means for rotating the shafts and rolls to move the sole margin lengthwise in a substantially vertical direction, 40 a pair of guides adapted to bear against the edge of the moving sole on opposite sides of the unrestrained path of movement of its gripped margin, to cause the sole to revolve with its edge in constant engagement with said guides, one of 45 said guides comprising a roller which is turned by contact with the sole edge, and means for applying blacking to said roller to black said edge.

6. Apparatus for blacking the edges of shoe soles, comprising a pair of horizontal shafts, one shaft being pivoted for angular movement with respect to the other, resilient means tending to 50 resist relative movement and to urge the shafts toward each other, opposed feed rolls carried by the respective shafts and adapted to grip the margin of the sole therebetween, means for rotating the shafts and rolls to move the sole margin lengthwise in a substantially vertical direction, 55 a pair of guides adapted to bear against the edge of the moving sole on opposite sides of the unrestrained path of movement of its gripped margin, to cause the sole to revolve with its edge in constant engagement with said guides, one of 60 said guides comprising a roller which is turned by contact with the sole edge, and means for applying blacking to said roller to black said edge, and independent means for adjusting the position of the respective guides with respect to the feed rolls.

ALBERT V. SHORTELL.
